FISHING LURE

Judson R. Bray, Rte. 1, Box 77, and Freddie L. Bray,
Rte. 1, Box 76e, both of Lexington, Mo. 64067

Filed Feb. 14, 1973, Ser. No. 332,244

Term of patent 7 years

Int. Cl. D22—05

U.S. Cl. D22—27

Fig. 1.

Fig. 2.

Fig. 3.

Fig. 4.

Fig. 5.

FIG. 1 is a plan view of a fishing lure showing our new design with the hook and head assembly shown in broken lines for illustrative purposes only;

FIG. 2 is a side elevational view of the lure;

FIG. 3 is a front view of the lure;

FIG. 4 is a rear view of the lure; and

FIG. 5 is a bottom view of the lure.

We claim:

The ornamental design for a fishing lure, as shown and described.
